FIG. 1 is a front perspective view of a pillow; FIG. 2 is a top plan view thereof;

FIG. 3 is a front elevation view thereof;

FIG. 4 is a bottom plan view thereof;

FIG. 5 is a rear elevation view thereof;

FIG. 6 is a right side elevation view thereof;

FIG. 7 is a left side elevation view thereof; and,

FIG. 8 is a front perspective view of the pillow of FIG. 1, showing our new design according to a second embodiment. The stipple shading in FIG. 8 represents a contrast of appearance.
